UNITED STATES PATENT OFFICE

168,163

DISH

Carl J. Lind, Evanston, Ill., assignor to Dairy Queen National Trade Association Incorporated, Davenport, Iowa, a corporation of Illinois

Application July 26, 1952, Serial No. 20,772

Term of patent 14 years

(Cl. D44—15)

To all whom it may concern:

Be it known that I, Carl J. Lind, a citizen of the United States, residing at Evanston, in the county of Cook and State of Illinois, have invented a new, original, and ornamental Design for a Dish, of which the following is a specification, reference being had to the accompanying drawing, forming part thereof, wherein:

Fig. 1 is a top plan view of a dish embodying my new design;

Fig. 2 is a side view thereof;

Fig. 3 is a cross-sectional view of the dish taken on the line 3—3 in Fig. 1; and

Fig. 4 is a similar view of the dish taken on the line 4—4 in Fig. 1.

I claim:

The ornamental design for a dish, substantially as shown.

CARL J. LIND.
